UNITED STATES PATENT OFFICE.

HAROLD F. ELLIOTT AND JAMES ARTHUR MILLER, OF PALO ALTO, CALIFORNIA, AS-SIGNORS, BY MESNE ASSIGNMENTS, TO FEDERAL TELEGRAPH COMPANY, OF SAN FRANCISCO, CALIFORNIA, A CORPORATION OF CALIFORNIA.

RADIOFREQUENCY SYSTEM.

Application filed January 9, 1922. Serial No. 527,886.

To all whom it may concern:

Be it known that we, HAROLD F. ELLIOTT and JAMES ARTHUR MILLER, citizens of the United States, and residing at Palo Alto, in the county of Santa Clara and State of California, have invented a certain new and useful Radiofrequency System, of which the following is a specification.

Our invention relates to radio frequency systems, and more particularly to systems in which are utilized arcs for converting electric energy in the form of direct current or of low frequency current into electrical energy in the form of high frequency current, suitable for radio signaling or other uses.

In such systems the conversion of energy is attended with losses inherent in the manner of operation of the arc. The efficiency at which the arc operates is dependent in a great measure upon the ratio between the effective value of the current through the arc and the E. M. F. across it. The ratio is in turn determined by the so-called current-voltage characteristic of the arc, which determines what the E. M. F. must be if the current is known, or vice versa. It has been attempted in the past to control the point of operation of the arc as regards its current voltage characteristic, and thus to fix the operation of the arc at the most efficient point. Such a scheme is shown in the patent granted to Leonard F. Fuller, Reissue No. 14,760 reissued November 25, 1919, entitled "Wireless telegraphy." The scheme involves the use of a special circuit branched around the arc. Although this may be acceptable for causing the arc to operate at a point differing a relatively small extent from the point at which the arc would operate without any branch circuit, still when for the sake of securing greater efficiency, it has been attempted to shift the point of operation further, such attempts have sometimes been futile due to the instability of the circuits. It is one of the objects of our invention to render the control of the current voltage characteristic of the arc surer and better. Another object is to render the operation of the arc as efficient as possible.

Investigations of such schemes as that shown in the Fuller patent referred to hereinbefore indicate that the control of the

point of operation is due in a measure to the transformer action of the circuits involved. Thus the primary or input circuit may be considered the antenna circuit together with the condenser in the arc circuit; the secondary, as this condenser and the condenser which is in the branch circuit. This secondary circuit is thus coupled to the main circuit. The condenser in the arc circuit is common to both the primary and the secondary. Current in the primary circuit causes current in the secondary, and this secondary current is in turn supplied to the antenna as well as the primary current. This transformer action, however, was not evident until further investigation that formed the basis for the present invention. It is thus seen that in order to control the arc current, by transformer action, a reactance of the proper value should be made to form a secondary circuit by being shunted across the arc, which reactance may be either capacitive or inductive. A reactance is also placed in the primary circuit which includes the arc, which reactance is common to both the primary and secondary. By properly proportioning the ratio of the reactance in the two branches, it is possible to cause any portion of the load to flow through the auxiliary branch circuit. For all practical purposes, it may be stated that the currents obey the law that in the two circuits they are to each other in inverse ratio to the impedance of the circuits; thus when the impedance of the branch circuit is low relatively to that of the arc circuit, the ratio of the total current to the arc current is high; in other words, the ratio of transformation is high. The system when operating at a high ratio of transformation has a tendency to become unstable. The instability may result in a tendency for the arc to operate at a frequency other than that desired, or in a tendency for cross currents to flow between the arc and the branched secondary circuit. Under such circumstances, we have found it advisable to use some kind of a stabilizer in order to prevent local or cross currents between the circuits as well as to confine the frequency of operation to a definite value.

The invention possesses other advantageous features, some of which, with the foregoing, will be set forth at length in the fol-

lowing description, where there will be outlined in full those forms of the invention which we have selected for illustration in the drawings accompanying and forming part of the present specification. In the drawings are shown several embodiments of our invention, but it is to be understood that we do not limit ourselves to such forms, since the invention, as expressed in the claims, may 10 be embodied in other forms as well.

Referring to the drawings:

Figure 1 is a wiring diagram of one embodiment of our invention, in which capacitive reactances are used in the branch circuits;

Fig. 2 is a wiring diagram of a modified form of our invention, in which inductive reactances are used in the branch circuits; and

Fig. 3 is a further modification bringing out more clearly the principles of operation involved.

In Fig. 1, the arc converter 11 is fed from mains 12 and 13 which carry either direct current or low frequency alternating current. The load circuit in the present instance includes the antenna 14, inductor 19, and the ground 15. A part only of the load current passes through the arc 11 and a reactance 16, in this case capacitive, in series therewith. The remainder passes through a branch or secondary circuit which also includes a capacitive reactance 17. As is customary, an electromagnet 18 of the proper strength is provided for influencing the arc. The reactances 16 and 17 are so proportioned that the desired current-voltage ratio or transformation ratio is obtained at the arc 11. The condensers 16 and 17 form substantially all of the impedances of the branch circuits. To stabilize the circuit and make it possible to obtain values of current-voltage ratios otherwise unattainable, we provide a stabilizing means 20. This is shown as consisting of two coils 21 and 22, one in each of the branch circuits, and so arranged on a common iron core 23 that their magnetizing forces substantially cancel each other while no local or cross currents exist 50 between the two branch circuits. When such local currents attempt to flow, there results a substantial magnetizing force, as is evident, and thus a correspondingly great core loss in the core 23. Since the currents normally choose such conditions of operation that there is the least energy loss, the cross currents can subsist for but a short period of time and cannot rise above a very small value. This means for stabilizing as 60 well as other forms which may be substituted therefor, are described and claimed in a co-pending application, Serial No. 527,885, in our names entitled Radio frequency system, filed Jan. 9, 1922, and assigned to 65 the same assignee as the present application.

The stabilizing means also eliminates the greater share of the higher harmonics, and in general makes it possible to improve the efficiency of the arc to an extent which may not be possible without it.

It is not essential that the reactances in the branch circuits be capacitive; the same result may be obtained with inductive reactances. Such an arrangement is shown in Fig. 2 where the inductors 24 and 25 are inserted in each of the branch circuits. The arc 11 sets up oscillations as before, and the high frequency current is made use of in the antenna signaling circuit comprising the antenna 14, coil 19, and the ground 15. The stabilizer 20 may also be used with the circuit. In this modification, the inductive reactances 24 and 25 may constitute the major portion of the inductance of the oscillating circuit. It is necessary, in case no condensers are used in the stabilizing circuit 20, to provide a stopping condenser 26 in one of the branch circuits to prevent current from the source from circulating through the reactances 24 and 25.

The principle of transformer action is well exemplified in Fig. 3, in which a further modification is shown. The inductor 27, condenser 28, and coil 30 are connected in series to the arc 11, and constitute the primary circuit. The secondary circuit comprises the earth connection 15, the lower portion of coil 30, the loading inductor 19 if necessary, and the antenna 14. It is thus seen that the coil 30 is used as an auto-transformer, although, as is self evident, a conventional type of transformer may be substituted therefor. By the aid of a single coil, as 30, instead of separate primary and secondary coils, closer coupling is effected 105 with attendant increase in efficiency.

It has been found, however, and may be readily checked mathematically that such a closely-coupled circuit is resonant to two isolated frequencies. The inductor 27, condenser 28, and the resistance 29 are introduced into the circuit to stabilize the system and insure operation at the desired frequency. The inductor 27 and condenser 28 are for this purpose tuned to make that portion of the circuit bridged by the resistance 29 resonant at the desired frequency. That is to say, at that frequency, the impedance drop across arc 11, inductor 27, and condenser 28 is a minimum. Under this condition of operation, the energy dissipated in the resistance is a minimum. An appreciable deviation from the desired frequency causes a substantial increase in the energy dissipated. Since the system inherently 120 tends to operate under such conditions that there is least energy loss, there is an immediate return to the desired frequency.

One of the advantages attendant upon the use of this invention is that the current

through the source is reduced, and smaller capacity signaling circuits may be used, as well as the apparatus in the circuits.

We claim:

- 5 1. In a radio frequency electrical system, a source of high frequency oscillations, a load circuit supplied from said source, a circuit offering a path for the load current free of the source, said path serving to increase the efficiency of the source and consisting solely of impedance, and means cooperating with said impedance for preventing the flow of any local currents between the source and the path.
- 10 2. In a radio frequency electrical system, an arc converter, a load circuit supplied from the converter, a circuit offering a path for the load current free of the converter and serving to increase the efficiency of the arc operation, said path consisting only of impedance, and means cooperating with said impedance for preventing the flow of local currents between the converter and said path.
- 15 3. In a radio frequency electrical system, an arc converter, a load circuit supplied from the arc converter, a circuit paralleling the arc converter consisting only of impedance, for increasing the efficiency of the arc operation, and a stabilizer for preventing the flow of local currents between the converter and said path, comprising an energy consuming device arranged to increase the energy loss therein upon the occurrence of such local currents.
- 20 4. In a radio frequency electrical system, a radio frequency arc, a circuit paralleling the arc circuit and offering a path free of the arc for a portion of the load current, the impedances of the two circuits being fixed at such values that the arc operates

at a relatively efficient part of its current-voltage characteristic, and means for preventing the flow of any local currents between the parallel paths.

45 5. In a radio frequency electrical system, an arc converter, a load circuit supplied from the arc converter, a circuit paralleling the arc converter consisting only of impedance, for increasing the efficiency of the arc operation, and a resistor connecting a point in the parallel circuit to a point in the arc converter branch for increasing the energy loss upon the occurrence of local currents between the parallel circuit and the arc converter.

50 6. In a radio frequency electrical system, an arc converter, a tuned circuit in series with the converter, an impedance also in series with the converter, a load circuit closely coupled to the impedance, and a resistor connected in parallel to the impedance.

60 7. In a radio frequency electrical system, a radio frequency arc, an oscillatory circuit connected to the arc, a circuit consisting substantially entirely of inductive reactance paralleling the arc circuit and offering a path free of the arc for a portion of the load current, an inductive reactance in the arc branch circuit, forming substantially all of the impedance of that circuit, the impedances of the two branched circuits being fixed at such values that the arc operates at a relatively efficient part of its current-voltage characteristic, and means for preventing the flow of any local currents between the parallel branch circuits.

70 75 In testimony whereof, we have hereunto set our hands.

HAROLD F. ELLIOTT.
JAMES ARTHUR MILLER.
